[57] CLAIM

The ornamental design for a pump dispenser, as shown and described.

DESCRIPTION

FIG. 1 is a left side elevational view of a pump dispenser showing my new design;
FIG. 2 is a front elevational view thereof;
FIG. 3 is a top plan view thereof;
FIG. 4 is a bottom plan view thereof;
FIG. 5 is a front elevational view of a second modified embodiment;
FIG. 6 is a side elevational view, shown with the cap removed for clarity of illustration;
FIG. 7 is a front elevational view thereof;
FIG. 8 is a top plan view thereof;
FIG. 9 is a bottom plan view thereof.

FIG. 1

FIG. 2

FIG. 3

FIG. 4

FIG. 5

FIG. 6

FIG. 7

FIG. 8

FIG. 9
